CLAIM

The ornamental design for a packing case as shown and described.

DESCRIPTION

1. Packing case

1.1 : Perspective

1.2 : Front

1.3 : Back

1.4 : Left

1.5 : Right

1.6 : Top

1.7 : Bottom

This design is used by placing the Tesla vehicle adapter inside the box for storage without shaking; this design is the main point of the creation of the interior case for the packaging box.
